R. OFFROY,
APPARATUS FOR TRIMMING THE SELVAGES OF WOVEN FABRICS IN LOOMS.
APPLICATION FILED JUNE 4, 1914.

UNITED STATES PATENT OFFICE.

RENÉ OFFROY, OF MALAUNAY, FRANCE.

APPARATUS FOR TRIMMING THE SELVAGES OF WOVEN FABRICS IN LOOMS.

1,187,168.

Specification of Letters Patent. Patented June 13, 1916.

Application filed June 4, 1914. Serial No. 842,866.

To all whom it may concern:

Be it known that I, RENÉ OFFROY, citizen of the French Republic, residing at Malau-
5 nay, Seine-Inférieure, France, have invent-
ed certain new and useful Improvements in
Apparatus for Trimming the Selvages of
Woven Fabrics in Looms, of which the fol-
lowing is a specification.

In looms provided with apparatus for the
10 automatic replenishment of the weft, it has
already been proposed to trim the selvages
of the fabric in the loom by cutting away
the loose threads occasioned along the said
selvages by the beginning and ends of the
15 cops.

Various devices have already been de-
signed with this object, but their delicacy
of adjustment or their fragility and the in-
complete work done by them, have greatly
20 restricted their use.

This invention has now for its object to
provide an improved and strongly construct-
ed selvage-trimming apparatus which will do
the work as perfectly as possible by cutting
25 away the loose weft ends left by the empty
cops as well as those of the fresh cops, and
which will work equally well in looms work-
ing without weft-feelers.

The improved selvage-trimming appara-
30 tus comprises the following features:—(1)
It is mounted on the slide-bar of the temple
behind the porcupine roller box; (2) It uti-
lizes the contraction of the fabric on leav-
35 ing the temples to cause the threads to be
cut to pass into the cutting device; (3) the
actuation of the cutting device is effected
by utilizing the recoil of the temple into its
spring box at each stroke of the slay; (4)
40 the cutting devices consist of a fixed blade
and a rotary disk provided with a number of
hooked fingers that constitute shear blades
adapted all to move successively across the
fixed blade.

One construction of the improved trim-
45 ming apparatus is illustrated by way of
example in the accompanying drawings, in
which:—

Figure 1 is an inner side elevation of a
50 loom temple provided with the trimming
apparatus; Fig. 2 is an outer side elevation
of the same temple; Fig. 3 is a plan of the
temple showing the mounting of the parts
55 of the trimming apparatus. In this figure
a portion of the fabric is shown in course
of manufacture so as to illustrate its
contraction on leaving the temple.

In the example shown, 1 is the box of the
loom temple with its porcupine roller 2
mounted in the usual manner upon the slide-
bar 3 which is adapted to slide in its box 4 60
fixed to the frame of the loom.

5 is a stop on the arm 3; it is adapted to
receive the blow of the slay of the loom,
whereby the temple is forced back into its
spring box at each stroke of the slay. 65

The cutting mechanism includes a fixed
cutting blade 6 with a pressure adjusting
member 7 fixed to the arm 3 immediately
behind the porcupine roller box. Slightly
70 behind this blade on a shaft 8 which ex-
tends from side to side through the arm 3,
there is mounted a disk 9 provided with
fingers 10 of hook shape, having their inner
edges 11 formed as cutting edges adapted
75 to coöperate with the blade 6 so as to act
as cutting-shears.

A disk 12 is mounted on the shaft 8. This
disk 12 and the disk 9 forms as it were, the
two flanges of a reel upon the barrel of
which the loose ends of the threads cut by 80
the shears are arranged to be wound. By
means of this arrangement the cut-off ends
of the threads are drawn outside the porcu-
pine roller box of the temple so that the lat-
ter is always cleared. 85

A ratchet wheel 14 is fixed by means of
a nut 13 on the shaft 8 on the outer side of
the sliding arm 3. This ratchet wheel 14 is
actuated by a pawl 15 which is mounted on
the spring box 4 and held in contact with the
90 teeth of the ratchet wheel 14 by a spring 16.
A spring pawl 17 holds the ratchet wheel
fast during the shifting of the pawl 15.

18 is the woven tissue drawn through the
tefipple. 19 are the warp threads and 20 is 95
the selvage thereof. Owing to the contrac-
tion of the fabric the selvage has a tendency
to move inward in the loom on leaving the
temple. 21 are the weft threads, the loose
ends 22 of which are to be cut off. 100

The operation of the trimming apparatus
is as follows:—Each beating-up of the slay
produces by means of the stop 5 a recoil of
the temple, the selvage 20 owing to contrac-
tion, has a tendency to move away from the
arm 3 toward the interior of the loom.
Owing to this contraction the thread to be
cut which is guided in a notch 23 formed in
the lower part of the box 1 of the temple 110
moves away from the selvage and takes up
a position which is inclined relatively to the

selvage. This position of the thread, allows it as the fabric moves toward the take-up beam to intersect the plane of the disk 9 at a certain angle and to be engaged and drawn by the hooks 10 and to be finally cut between the cutting edges of the fixed blade 6 and the edges of the hooks 10. The rotation of the fingers is produced by the rotation of the ratchet wheel which moves forward one tooth at each stroke of the slay. This arrangement allows of cutting the threads 22 as closely as desired to the selvage by simply adjusting the position of the disk more or less closely to the selvage 20.

15 It is to be understood that the construction of the improved trimming apparatus may be modified without departing from the nature of this invention and also that modifications may be made in the use of the apparatus which may be arranged on both sides of the loom.

20 Having now particularly described and ascertained the nature of my said invention and in what manner the same is to be performed, I declare that I claim—

25 1. The combination, with a loom having a loom temple comprising a box and a toothed roller therein carried by a slide-bar resiliently mounted on the frame of the loom, of a weft cutting device comprising fixed and movable cutter blades mounted on said slide-bar to the rear of said roller a sufficient distance to permit a partial contraction of the fabric after it leaves the loom 30 temple and before the loose weft threads of the fabric reach said cutting blades, and a guide on said temple for the loose weft threads for positioning them in the path of said cutting blades.

35 2. The combination, with a loom having a loom temple comprising a box and a toothed roller therein carried by a slide-bar slidably mounted on the frame of the loom and means including the slay of the loom for imparting to said temple a reciprocating movement, of a weft cutting device mounted on said slide-bar comprising a rotary cutting blade, a pawl and ratchet connection part of which is positioned on said slide-bar 40 and part on the stationary frame for actuating said rotary cutting blade upon reciprocating movement of said slide-bar, a reel

55 rotatable with said cutting blade, said cutting blade forming one of the flanges of said reel, and a guide on said temple for positioning the loose weft threads in the path of said cutting blade.

60 3. The combination, with a loom having a loom temple comprising a box and a toothed roller therein carried by a slide-bar slidably mounted on the frame of the loom, of a weft cutting device positioned to the rear of said toothed roller and between the slide-bar and the selvage of the fabric in the loom, means positioned in part on said slide-bar and in part on said stationary frame for actuating said cutting device upon a reciprocatory movement of said slide-bar means for reciprocating said slide-bar including a member adapted to be engaged by the slay 70 of the loom, and a guide on said temple for positioning the loose weft threads in the path of said cutting blade.

75 4. The combination, with a loom having a loom temple comprising a box and a toothed roller therein, of means for cutting the loose ends of the weft thread comprising a cutting device arranged to the rear of said loom temple a sufficient distance to permit a partial contraction of the fabric as it leaves 80 said loom temple before the loose weft threads are engaged by said cutting device and a guide on said temple for positioning the loose weft threads in the path of said cutting blade.

85 5. The combination, with a loom having a loom temple comprising a box and a toothed roller therein, of a weft cutting device comprising a fixed blade mounted to the rear of said toothed roller, a rotary cutting blade comprising a disk having a plurality of radiating cutting blades with hooked ends, a reel rotatable with said cutter, said disk forming one of the flanges of said reel and a guide on said temple for 90 positioning the loose weft threads in the path of said cutting blade.

95 In testimony whereof I affix my signature in presence of two witnesses.

RENÉ OFFROY.
